UNITED STATES PATENT OFFICE.

SAMUEL BRUCE, OF HELVETIA, PENNSYLVANIA.

ELEVATOR.

No. 902,371.

Specification of Letters Patent.

Patented Oct. 27, 1908.

Application filed October 17, 1907. Serial No. 397,862.

To all whom it may concern:

Be it known that I, SAMUEL BRUCE, a citizen of the United States, residing at Helvetia, in the county of Clearfield and State of Pennsylvania, have invented new and useful Improvements in Elevators, of which the following is a specification.

This invention relates to elevators and it has particular reference to an improved safety appliance which is designed, in the event of breakage of the hoisting cable, to engage the side walls or the guide rails in the elevator shaft and to prevent the cage or car from dropping or descending into the shaft.

A further object of the invention is to provide simple and efficient means for regulating the tension of the operating spring of the safety appliance.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a perspective view of an elevator car or cage equipped with the improved safety appliance, the car being shown in operative position between the guide rails. Fig. 2 is a side elevation partly in section. Fig. 3 is a vertical sectional view taken through the casing of the actuating spring and related parts.

Corresponding parts in the several figures are denoted by like characters of reference.

The elevator car or cage, C, comprises the side members or uprights 1—1, the sills 2—2, the floor 3 and the cap beam 4, which connects the upper ends of the side members. The latter are vertically grooved in the usual manner to engage the guide rails 5—5, which latter extend vertically through the elevator shaft in the usual manner.

Firmly bolted or otherwise secured upon the cap beam 4 in registry with the vertical aperture 6 in said cap beam is a tubular casing 7 which is preferably of cylindrical

shape and provided at its lower edge with an annular flange 8 for the passage of the bolts or fastening members 9 whereby the casing is secured upon the cap beam. The upper end of the casing 7 is exteriorly screw threaded for the reception of an interiorly screw threaded cap 10 having a central aperture surrounded by a guide flange 11 through which is guided a stem 12, the lower extremity of which is enlarged to form a head 13 which is guided in the aperture 6 of the cap beam; said head and aperture being preferably of non-circular cross-section. The stem 12 is provided with an annular flange or collar 14, and upon said stem, between the flange 14 and the cap 10 there is coiled a powerful helical spring 15. It will be readily seen that the tension of this spring may be regulated by properly adjusting the cap 10 upon the screw threaded casing 7 since, by moving the cap in an upward direction additional room is given for the spring to expand.

The upper extremity of the stem 12 is connected by a link or clevis 16 with the lower end of the flexible hoisting element 17; the weight of the car or cage will thus be supported upon the spring 15 which latter, by the weight of the car, is compressed between the flange 14 and the cap 10, which latter has been previously adjusted to regulate the tension of the spring. The lower end of the hoisting element 17 is connected by flexible elements such as chains 18 with the cap beam 4; said chains being of such length that, when the car or cage is loaded, they will become taut, thus relieving the spring and preventing injury to the latter from being overloaded.

The head or enlargement 13 at the lower end of the stem 12 is provided with dogs 19 pivotally connected therewith, and guided through apertures 20 in the side members of the car or cage; the sharp pointed extremities of said dogs being adapted to engage the uprights or guide rails 5—5. It will be understood, however, that under normal conditions, the pointed extremities of the dogs 19 will clear the rails 5—5, the weight of the car or cage being sufficient to move it downward against the tension of the supporting spring 15 to compress the latter to some extent, permitting the stem 12 to move in an upward direction sufficiently to move the dogs 19 clear of the rails, as described. In the event, however,

of breakage of the hoisting element 17, the spring 15 will instantly expand, forcing the stem 12 in a downward direction, and forcing the pointed extremities of the dogs 19 into active engagement with the rails 5-5, thus checking and preventing the descent of the car.

This improved safety appliance is extremely simple in construction and efficient 10 in operation; and the actuating spring also serves to support the weight of the car or cage, making a resilient connection between the latter and the hoisting element.

Having thus fully described the invention, what is claimed as new is:—

15 An elevator car having side members and a cap beam, the former provided with guide openings and the latter with an aperture, a cylindrical casing secured upon the cap beam in registry with the aperture, a screw

threaded cap adjustably connected with the casing, a stem guided through the cap having an annular flange and a head or enlargement, the latter guided in the aperture in the cap beam, normally inclined dogs connected pivotally with the head or enlargement and slidably and pivotally mounted in the guide openings in the side members of the car, a spring coiled upon the stem between the annular flange and the adjustable 25 cap of the casing, a flexible hoisting element connected with the upper end of the stem, and auxiliary flexible elements connecting the hoisting element with the cap beam.

In testimony whereof I affix my signature 30 in presence of two witnesses.

SAMUEL BRUCE.
